UNITED STATES PATENT OFFICE.

SIMON COOPER, OF BROOKLYN, NEW YORK, ASSIGNOR TO IDEAL WRAPPING MACHINE COMPANY, A CORPORATION OF NEW YORK.

WRAPPER OR WEB FEEDING MECHANISM.

Original application filed May 14, 1920, Serial No. 381,453. Divided and this application filed November 18, 1922. Serial No. 601,725.

This invention relates to a wrapper or web feeding mechanism for candy wrapping machines, in which the wrapper is intermittently fed forward through a pair of co-operating feed rolls to a chute or platform over which the sticks of candy are caused to pass as they are fed into the machine.

This application is a division of my co-pending application Serial No. 381,453, filed May 14th, 1920.

It is an object of this invention to provide a novel, simple and improved wrapper feeding mechanism that is intermittently operated for feeding a predetermined strip of paper from a reel for wrapping a stick of candy.

This invention comprises the novel mechanisms and combinations hereinafter described and more particularly pointed out and defined in the appended claims.

In the accompanying drawings, which illustrate a preferred embodiment of this invention, and in which similar reference numerals refer to similar features in the different views:

Figure 1 is an elevational view of a bracket or frame member that supports the paper feeding mechanism and that forms part of the candy wrapping machine disclosed in my aforementioned application.

Figure 2 is a sectional view through a part of said machine illustrating the driving mechanism for the paper feeding mechanism in elevation.

Figure 3 is an enlarged transverse section through the paper feeding rolls showing the bracket in elevation.

Figure 4 is an enlarged longitudinal section through the paper feeding mechanism.

Figure 5 is an elevational view of the roller clutch member.

As shown on the drawings:

In referring now to the drawings, the reference numeral 1 indicates a frame or bracket having an upper bracket member 1^a secured or pivoted thereto. These brackets form part of the candy wrapping machine illustrated in my copending application. A reel 2 is rotatably supported in the frame 1 and the paper 2^a which forms the wrapper, and which is commonly called the web, for wrapping the candy is led therefrom over a guide roll 3 supported on an arm 4 extending from the frame. From the guide

roll 3 the web of paper is led downwardly over a tension roll 5 rotatably supported upon an arm 6 pivoted at 7 to the frame 1 and provided with a brake element 8 at the end opposite the roll 5 for bearing against the reel 2. From the tension roll 5, the web is led upwardly over a guide roll 9 rotatably supported in the top bracket 1^a and from the guide roll 9, the paper web is passed between the feed rolls 10 and 11.

In referring to Fig. 4, it will be observed that the feed rolls are provided with circular grooves 12 whereby the peripheries are divided into spaced contacting portions. The spaced contacting portion 13 at one end of the roll 10 is adapted to be moistened by a rotary moistening element 14 rotatably mounted in a fluid container 15 and projecting through a slot in the bottom thereof. Bars 16 and 17 are supported with their ends within the grooves 12, as shown in Fig. 3. These bars serve as strippers to prevent the paper web from being wound around the rolls and they also serve as a guideway for the web.

The roll 10 is provided with end journals which are rotatably mounted in bearing blocks 18 which are supported in guideways or boxes in the frame 1^a. The upper ends of these blocks are provided with bearing recesses for receiving the ends of the spindle 18^a that extends through the fluid container and that has the moistening element 14 keyed or secured thereon and that supports the fluid container. A gear 19 is secured upon the spindle 18 and this gear is driven by a gear 20 secured to the hub of the roll 10. The gear 20 is in turn driven by a gear 21 secured upon the hub 22 of the lower feed roll 11.

The hub 22 of roller 11 is illustrated as provided with an annular flange or abutment 22^a upon which the gear 21 is secured, the web of the roll 11 being clamped against said flange by a nut 23 adjustably threaded upon the hub. The adjacent end of the hub 22 is rotatably journalled in a bearing formed in the casing 1^a. The front or right-hand end of said hub is provided with a clutch face, as shown more clearly in Fig. 5. This clutch face is provided with two opposite slopes or cam surfaces that terminate in diametrically opposite shoulders 24 which are adapted to be engaged by two diametri-

cally opposite spring-pressed plungers 25 5
slidably supported in suitable bores in a
head 26 keyed upon one end of a shaft 27
loosely extending through the hub 22 and
journalled at its other end in a bearing
formed in the bracket 1^a. It will be ap- 10
parent that as the shaft 27 is rotated in one
direction, in an anti-clockwise direction in
the present instance, the inner ends of the
plungers 25 will engage the shoulders 24 and
rotate the roll 11 in one direction, and that
when the shaft 27 is rotated in the opposite
direction, the plungers 25 will ride up the
cam surfaces and out of engagement with
said shoulders, and as long as the shaft 27
rotates in this opposite direction there will
be no rotation imparted to the roll 11. The
shaft 27 may therefore be said to be con- 20
nected to the roll 11 through a uni-direc-
tional clutch.

The end of the shaft 27 opposite the head
26 extends through the bracket 1^a where it
has a pinion 28 keyed thereon whereby the
said shaft may be rotated. Mechanism has
been provided for alternately rotating the
shaft 27 in opposite directions, and in the
form shown this mechanism consists of a
spirally grooved cam 29 (Fig. 2) secured
upon the driven shaft 30 which is driven in
a suitable manner by a motor or the like. A
roller 31 is positioned within the cam
groove, and supported upon an arm 32 ex-
tending from a bearing sleeve 33 journalled
upon a short shaft 34 suitably supported by
the frame of the machine. A link 36 con-
nects the arm 32 with a second arm 37 ex-
tending from a sleeve 38 journalled upon a
stub shaft 39 suitably journalled in the
frame-work of the machine. 30
The end of the arm 37 is provided with a
segment gear or rack 40 (Fig. 4) that
meshes with the pinion 28 on the shaft 27.
It will be apparent that rotation of the cam
29 will oscillate the arm 32 backwards and
45 forwards imparting a similar movement to
the segment arm 37 connected thereto by the
link 36, and as the arm 37 is oscillated back-
ward and forward, it will oscillate the shaft

27 which, during an anti-clockwise rotation,
will rotate the roll 11 and through gears 21
and 20 will rotate the roll 10, and through
the gears 20 and 19 the moistening element
14 will be oscillated. As the shaft 27 is os-
cillated in a clockwise direction, the rolls
and moistening element will remain idle on
account of the unidirectional clutch, as previ-
ously explained. 55

From the foregoing it will be obvious
that an efficient and simple web feeding
mechanism for a candy wrapping machine
has been provided in which the liability of
the wrapping paper winding around the
rolls is avoided, and in which the wrapping
paper is intermittently fed forward by an
alternately rotatable shaft and in which the
wrapping paper or web is evenly advanced. 60

I am aware that numerous details of con-
struction may be varied through a wide
range without departing from the prin-
ciples of this invention, and I therefore do
not purpose limiting the patent granted
otherwise than necessitated by the prior art. 70

I claim as my invention:

1. In a candy wrapping machine, a pair
of intergeared web feeding rolls, one of said
rolls being provided with a hub having a
uni-directional clutch face upon one end, a
bearing in which one end of said hub is
journalled, a shaft loosely extending through
said hub, a head keyed upon said shaft,
spring-pressed plungers carried by said
head and adapted for clutching engagement
with said hub during one direction of rota-
tion of said shaft, and means for oscillating
said shaft. 75

2. In a candy wrapping machine, a pair
of intergeared web feeding rolls, one of said
rolls having an end in the form of a uni-
directional clutch, a shaft loosely extending
through the last mentioned roll, a head se-
cured upon said shaft, and plungers yield-
ingly mounted in said head for coaction
with said clutch face. 80

In testimony whereof I have hereunto
subscribed my name.

SIMON COOPER.
